GLOW LAMP

Fritz Michelassen and Fritz Schröter, Berlin,
Germany, assignors to Telefunken Gesellschaft
für Drahtlose Telegraphie m. b. H., Berlin, Ger-
many, a corporation of Germany

Application July 8, 1930, Serial No. 466,406
In Germany July 10, 1929

2 Claims. (Cl. 176—122)

It has heretofore been known that a luminous column such as that produced from glow-discharge or gaseous-conduction lamps or tubes emits much more light in longitudinal direction than in right angles thereto. This is due to the fact that in longitudinal direction the light given off by the individual ions becomes integrated. This property could be utilized for a great number of purposes, for instance, in picture-teleg-
raphy work, television and the phono-film art, where such a glow-discharge lamp is employed for the object of converting electric impulses into light in a way free from sluggishness. However, when using glow-discharge lamps comprising elec-
trodes having a form as heretofore usual, the problem of leading-in or supplying the current has been attended with certain difficulties, and these are to be obviated by the present invention.

In the case of picture telegraphy the form of construction illustrated in the accompanying drawing has proved advantageous, it being understood, of course, that this embodiment could be used also for many other purposes. The drawing shows by Fig. 1 a longitudinal cross-section through anode and cathode of the glow-discharge lamp, while Fig. 2 represents a transverse cross-section through Fig. 1 on the line 2—2 thereof and Fig. 3 represents a view similar to Fig. 2 but of a modified form of tube electrode construc-
tion.

Making specific reference to Figs. 1 and 2 of the drawing, the cathode K has the form of a hollow cylinder of suitable cross-section and convenient length, and the outer wall and current-
lead L₁ thereof is insulated or separated from the gas filling by a glass vessel G. Also, the anode A supplied with current through lead L₂, insulated in a similar manner to lead L₁, is sep-
arated from the cathode K. The entire assem-
bly is contained within a gas filled container or envelope C.

If the distance between anode and cathode and the pressure of the gas filling have been correctly chosen, then, on switching in the current, the first glow discharge will occur in the part of the cathode capillary closest to the anode. As the current grows in value, the cathode glow-layer also will grow and finally extend as far as the points of the cathode most remote from the anode. Since an examination of the luminous column is possible only in the direction of the cylinder axis, the cathode glow becomes more intense when the current is large than when it is small.

If the anode is designed in the form of a di-

aphragm, it is possible to allow the glow light to act through this diaphragm. However, so far as the modulation of the light at the rhythm of the electric impulses is concerned, this scheme involves an inconvenience. The luminous intensity coming to act from the different points of the glow capillary is governed by the opening or aperture depending upon the cross-sectional area and the distance from the diaphragm. As the distance from the diaphragm increases, also the angle of aperture decreases. In such an arrangement the glow-discharge lamp operates with a fairly large initial volume of light and with slow growth of luminous intensity as the current increases.

In order that the luminous variations corresponding to the variations of the current may be made as large as possible, it is necessary to cause light to act also from the opening of the capillary opposite (or turned away from) the anode in the manner disclosed by this invention. The glow light due to smaller currents is formed in the vicinity of the anode and presents a small angle of aperture. But as the current grows, also the angle of aperture of fresh glow layers becomes larger, and the luminous intensity increases. The effect of the integration of the light in longitudinal direction of the capillary tube, and the increase in the aperture as the current increases become superposed and added to each other so that a better reproduction of modulation of the electric current by the glow-light is possible. A curve giving the inter-relationship between current and brightness presents a greater steepness when the glow issuing from the opening turned away from the anode comes to act than when it acts through the anode designed to serve as a diaphragm.

The same principle is applicable, of course, also to forms of construction as used, for instance, in recorder lamps employed in making speaking films. It is to be remembered that what is required in that case is not a punctiform, but rather a linear, conversion of electric current into light. The hollow cathode then no longer is a cylindrical capillary tube, as just described, but the same rather presents the shape of a flattened ellipse in cross-section, as shown by Fig. 3. The outer wall is insulated so that cathode glow is able to develop here also only in the inner space.

From the above description, it is, of course, obvious that many modifications and changes may be made in the structure therein disclosed without departing from the spirit and scope of the invention, and we, therefore, believe ourselves to be

entitled to make and use any and all modifications such as would readily suggest themselves to those skilled in the art to which the invention relates.

5 Having now described our invention, what we claim and desire to secure by Letters Patent is the following:

1. In a glow lamp construction, an elongated hollow cathode body having a uniform elliptical cross-sectional formation throughout its length, an anode arranged to cooperate with said cathode, and a layer of insulating material surrounding said cathode.

15

2. A glow lamp comprising a tubular cathode member open at each end and of uniform cross-sectional area throughout its length, an anode supported at one end of said open tubular cathode and masking the light from said end, a layer of insulating material surrounding the outer surface of the said open-ended tubular cathode, and a gas-filled container surrounding both said anode and cathode.
